UNITED STATES PATENT OFFICE.

NICHOLAS H. BORGELDT, OF NEW YORK, N. Y., ASSIGNOR TO THE AMERICAN FLEXIBLE LIFE SAVING RAFT ASSOCIATION.

IMPROVEMENT IN LIFE-RAFTS.

Specification forming part of Letters Patent No. 175,019, dated March 21, 1876; application filed February 19, 1876.

To all whom it may concern:

Be it known that I, NICHOLAS HERMANN BORGELDT, of New York city, in the county and State of New York, have invented a new and Improved Life-Raft, of which the following is a specification:

Figure 1 is a perspective view of my improved life-raft, showing it applied to the side of a vessel. Fig. 2 is a detail top view of part of a float, and of the reticulated bags adjoining the same. Fig. 3 is an end view of the same. Fig. 4 is a detail vertical longitudinal section, on an enlarged scale, of the same.

Similar letters of reference indicate corresponding parts in all the figures.

This invention relates to a life-raft, which contains features of improvement over the raft described in my Letters Patent No. 146,426, of January 13, 1874.

My present invention consists, first, in substituting for the continuous aprons described in said former patent a series of reticulated or other bags or receptacles, applied between the traverses and the floats, in such manner as to render the raft reversible. When the float, having the continuous apron described in said former patent, is thrown overboard, and happens to fall with the traverses below the apron, the object of the latter as a receptacle for passengers between the floats is defeated, and the utility of the entire raft materially reduced; but with flexible bags applied between the traverses the raft is reversible, and will be in position for saving life in whichever manner it may be thrown into the sea.

A second feature of improvement consists in the combination of the jointed floats, which are united by traverses, with a rope ladder, which will serve as a means of escape from a wrecked or other injured vessel to the float. By the use of the said ladder, which constitutes a permanent attachment to the raft while on board ship, I am enabled to utilize the whole length of the raft for life-saving purposes, while in my former patent a large part of the raft was made to constitute the ladder, and was therefore not immediately applicable to its final purpose; yet, after the passengers have left the ship, the rope ladder can be readily detached from the raft to prevent the lat-

ter from sinking with the ship, while the direct connection of the raft with the ship shown in my former patent, made the final detachment a matter of extreme difficulty and great peril to the persons undertaking the same.

In the accompanying drawing, the letters A A represent the rows of jointed floats, which are connected by cross-bars or traverses B B, substantially as described in my former patent. Between every pair of floats A A the spaces between the respective traverses are filled with flexible bags or receptacles C C, which I prefer to construct of reticulated material, as indicated in the drawing. These bags are attached with their ends to the floats A A and to the traverses B B, so as to form flexible receptacles within the open spaces formed by said floats and traverses.

When the float is on the water, as in Fig. 1, either side up, the bags will constitute depressed receptacles for the persons on the raft.

D D are ropes, that may be fastened to the sides of the floats A A, and can be used as guide-lines for persons standing or walking on the floats, and may also be grasped by the persons in the bags C, to prevent them being washed off the raft by a heavy sea. E is a rope ladder, fastened by cords a a, or otherwise in easily-detachable manner, to one end of the raft. This ladder as long as the raft is kept on board is to be a permanent attachment of the same. When for use, the ladder E is, with its upper end, secured to the gunwale, rail, or side of the vessel, while its lower end connects with the raft, as in Fig. 1; it will enable the persons on board ship to easily reach the raft. I propose to make this ladder of nearly the same width as the raft, so it may be used by a considerable number of persons simultaneously; but in order to prevent its lateral collapse while in use, and also to make it more convenient for persons unskilled in the use of rope ladders, I propose to secure in the rope ladder a series of stiff rungs or cross-bars, b b, of wood, metal tubing, or equivalent material, which stiff rungs will alternate with the flexible rungs of the ladder, as indicated; but the rope ladder may also be made without the stiff rungs.

When the raft is cut loose, it is only neces-

sary to cut or unfasten the connecting cords or fastenings *a a* between the ladder and the raft.

Suitable lines should be provided on the raft to enable boats of rescue to be fastened thereto.

I claim as my invention—

1. A life-raft composed of two or more sets of jointed floats, which are connected by traverses, and of a series of reversible bags, *C C*, in the spaces formed by said floats and trav-

erses, substantially as herein shown and described.

2. The combination of the life-raft, composed of the floats *A A* and traverses *B B*, with the rope ladder *E*, which is an attachment of said raft, substantially as and for the purpose specified.

NICHOLAS H. BORGFELDT.
